UNITED STATES PATENT OFFICE.

GEORGE A. SHOEMAKER, OF URBANA, VIRGINIA, ASSIGNOR OF ONE-HALF TO GEORGE VAN WAGNEN, OF URBANA, VIRGINIA.

TRAIN SIGNALING APPARATUS.

No. 823,719.

Specification of Letters Patent.

Patented June 1, 1909.

Application filed May 25, 1907, Serial No. 375,656. Renewed October 8, 1908. Serial No. 466,832.

To all whom it may concern:-

Be it known that I, GEORGE A. SHOEMAKER, a citizen of the United States, residing at Urbana, in the county of Middlesex and State of Virginia, have invented new and useful Improvements in Train Signaling Apparatus, of which the following is a specification.

This invention is an improved train signaling apparatus for use on the rear end of a car or train to prevent rear-end collisions at night or in a fog, and it consists in the construction, combination, and arrangement of devices hereinafter described and claimed.

15 The object of my invention is to provide an exceedingly cheap, simple, and efficient signal which may be readily attached to the roof of a car and to the rail of the platform thereof for use in displaying an illuminated 20 disk of any suitable color or colors, and which, when not in use, may be readily folded up under the roof of the car above the platform and out of the way.

In the accompanying drawings:—Figure 1 25 is partly an elevation and partly a sectional view of one end of a car provided with my improved signaling device, showing the same in displayed position, as when in use, Fig. 2 is an end elevation of the same, Fig. 3 is a 30 vertical sectional view of the same on a larger scale, taken on a plane indicated by the line 3—3 of Fig. 2, and showing the signaling device in display position in full lines and folded up under the car roof out of the 35 way in-dotted lines. Fig. 4 is a detail front elevation of my improved signaling device, and Fig. 5 is a detail sectional view of the same, taken on the plane indicated by the line 5—5 of Fig. 3.

40 In the embodiment of my invention I provide an improved casing 1 to contain and display a color disk 2 and a lamp or lantern 3 to illuminate the said disk and cause the same to be plainly visible to the engineer of an approaching train. The said casing has a 45 face plate 4, which may be made of sheet or plate metal, is provided with a display opening 5, and is here shown as also provided with reinforce flanges 6—7, respectively disposed 50 around said opening and the edges of the said face plate.

On the front side of the face plate is secured a box or housing 8 of suitable size, shape, and construction, here shown as rectangular, and which is provided on its rear

side with a hinged door 9. The said door has a suitable catch 10 to fasten it when closed, and is provided on its inner side with a bracket 11, or other suitable means, to support the lamp or lantern 3. The said box or housing is provided in its front side with an opening 12, which is co-incident with the opening 5 and is provided with its upper and lower sides, immediately in rear of said opening 12, with the guide grooves 13 for the reception of the upper and lower sides of a frame 14, which is removable from the box or housing through an opening in one side thereof, and is provided at its outer side with a suitable handle 15. The disks, screen, or target 2, which may be made of colored silk, colored glass, or other suitable transparent or translucent material, is secured to the sides of the said frame 14. In practice the said disk may be of all one color, or it may 75 be of more than one color, as may be desired, or to conform to any established code of signals, which may be adopted by any railroad management.

The casing is adapted to be hinged at its upper end to the verge-board, or other suitable portion 16, of the projecting end of the car roof, which extends above the car platform. The face plate of the casing is provided at its upper corners with hinge lugs 17, which are pivotally connected by means of suitable pintles 18 to hinge straps or other suitable devices 18', which are here shown as secured to the inner side of the verge-board. At the lower corners of the face plate of the casing are catches 19, which are hinged thereto, as at 20, and the free inner or lower ends of which are provided with pairs of parallel arms 21 appropriately spaced apart and forming notches between them of sufficient size to receive the rail 22 of the car, as shown in Fig. 3. The said catches 19 are disposed in a horizontal position when thus engaged with the rail of the platform, and it will be understood that such catches will co-act with the hinge connections between the casing and the car roof to support the signaling device in the vertical position at the rear end of the car, where it will be plainly visible to the engineer of a train approaching from the rear and will serve to prevent rear-end collisions. When the catches 19 are disengaged from the rail 22 the signaling device may be swung upwardly and under the car roof out of the way, as indicated in dotted lines in Fig. 3, and

when thus disposed the said signaling device may be engaged by a suitable catch 23, with which the car is provided.

Any suitable number of the frames and disks may be provided for each of the signaling devices, to adapt any desired signal to be displayed. The frame 14, which carries the disk 2, being readily removable from the box of the casing, enables any desired signaling disk to be readily exchanged for another. The door 9, which carries the lamp or lantern, being hinged to the box, may be readily opened and closed to facilitate the placing of the lamp or lantern in the said box and its removal therefrom.

Having thus described the invention what is claimed as new, is:—

1. Train signaling apparatus comprising a casing for a light, said casing having a face plate provided with a display opening, a frame in and removable from the casing and having a signaling disk for illumination by the light, and a door provided with means to support the light.
2. Train signaling apparatus comprising a casing hinged at its upper end to a car roof,

over the rear end of the platform, and provided at its lower end with a hinged catch to engage the platform rail and support said casing in a vertical position, and means under the car roof to engage and hold said casing when the latter is swung up under the car roof.

3. Train signaling apparatus of the class described, comprising a casing for a light, such casing having a face plate provided with a display opening, a frame in and removable from the casing and having a signaling disk for illumination by the light, a door in the rear side of the casing provided with means to support the light, means at the upper end of the casing to hinge the same to a car roof, and a pivotally mounted catch at the lower end of such casing to engage the rail of the car platform and support such casing in a vertical position.

In testimony whereof, I affix my signature in presence of two witnesses.

GEORGE A. SHOEMAKER.
